ENGINE

Waldo G. Gernandt, Hayward, Calif.

Application March 6, 1931, Serial No. 520,564

2 Claims. (Cl. 123—33)

This invention relates to Diesel engines and more particularly to fuel injection units for engines of the Diesel type wherein the compressor unit is a complete assembly and adapted to be installed in detachable relation to the engine.

The present application is an improvement on my copending application No. 499,636, filed December 3, 1930, issued Jan. 1, 1935, as Patent No. 1,986,674, and in certain respects, differs therefrom by the manner in which the compressor discharge valves are operated.

An object of the invention is to provide a fuel injection unit that is adapted to entrap a portion of the fluid products of combustion from a cylinder of the engine during the expansion stroke and subsequently introducing it to the compressor wherein it is additionally compressed and discharged to the engine, the purpose of the engine charge being to augment the primary charge of fuel mixture which has been drawn into the compressor from another source.

A feature of the invention relates to the operation of the discharge valve of the unit, which in the illustrative embodiment, is not only opened to discharge fuel into the engine cylinder, but is also opened a second time in the same engine cycle to permit the high pressure gases within the engine cylinder to be forced back into the compressor and further compressed for discharge into a subsequent firing cylinder.

Other objects and features of the invention will be apparent from the following description of a preferred embodiment of the invention which I have illustrated in the following drawings in which:

Figure 1 is a vertical sectional view of the compressor unit; and

Figure 2 is a side elevation partly in section, of the injection unit shown in Figure 1; and

Figure 3 is a top plan view of the compressor with the head removed.

Referring to the drawings, 1 is a crank case to which is secured the compressor cylinder 2, having a removable head 5. Within the cylinder 2 is a reciprocating piston 3, secured to the crank shaft 4 by connecting rod 6. The compressor is connected to the engine (not shown) by driving shaft 8 which in turn drives the crank shaft 4 through gears 10 and 12, gear 12 having twice the number of teeth of gear 10, whereby the crank shaft 4 is rotated at twice the speed of the driven shaft 8.

Above the drive shaft 8 is mounted the cam shaft 14, which is driven by shaft 8 at one-half the speed of shaft 8, through gears 16 and 18.

Cam shaft 14 is provided with a series of four cams which are arranged in angularly spaced intervals of 90°, each cam having a pair of spaced lobes 20 and 21, whereby the respective valves 22 are lifted twice in each revolution by arms 24 pivotally mounted on case 1. Each of the valves is adapted to control an opening 28 that leads to a conduit 30 in communication with a fitting 32 leading to the working cylinders of the engine (not shown) to which the injection unit is secured.

Leading from the upper end of the compressor cylinder is a transverse passage 34 which intersects a longitudinal passage 36 which communicates with the chamber 38 (which is) provided underneath each of the respective valves. The passage 36 is preferably drilled through one wall of the cylinder and has its outer end closed by screw 37. An inlet passage 40 leads from a source of supply of exhaust gas or opens directly to the atmosphere, depending upon whether it is desired to charge the engine with a mixture of fuel and inert gas, or a mixture of fuel and atmospheric air.

The passage 41, between inlet 40 and the crank case 1, is unobstructed and gas may freely enter the crank case because of the suction produced therein by the outward or upward movement of the piston 3. The Venturi tube 44, in which is mounted the fuel jet 46, is located adjacent the spring loaded valve 48 and the gas used for atomizing the fuel only traverses the fuel jet opening on its way from the crank case to the cylinder.

The fuel is fed to jet 46 by means of a fuel pump 50 having an inlet 52 and an outlet conduit 54 which leads to the jet 46 by passageway 56 formed in the cylinder casting. The opening of the fuel jet is controlled by needle valve 58, which is controlled by a cam 60 rotatably mounted in bearing 62, secured to the valve cover 64 by screws 66, the shaft being rotated to raise and depress the needle valve by a lever 68.

In the operation of the invention, exhaust gas or air is drawn into the crank case by the upward movement of the piston 3, which upon descending, draws the gas upwardly through passage 41 past the fuel jet 46 from which it draws a supply of fuel controlled by the opening of the needle valve 58, and through the valve 48 into the compressor cylinder. The upward movement of the piston 3 compresses the fuel mixture within the cylinder until one of the fuel valves 22 is opened by the cam shaft, whereupon it flows to the working cylinder of the engine that corresponds to the respective distributor valve of the injection unit.

- The distributor valves 22 are operated by the cam shaft 14, which rotates at half engine speed and therefore, one of the distributor valves is opened twice during each revolution against the resistance of spring 23 by cam lobes 20 and 21. The arrangement of a single compressor cylinder driven at twice engine speed and a distributor valve mechanism which is driven at one-half the engine speed, permits the use of 5
- 10 a single compressor cylinder for a four cylinder engine, and each engine charge is of the same volume and quality, for any leakage which may develop in the compressor will affect all of the engine cylinders equally. Cam lobe 21 is ar- 15 ranged in a clockwise direction with respect to lobe 20 and in position to lift valve 22 a second time after about 35 degrees of cam rotation, or 70 degrees of engine rotation. The lifting of the valve by the cam lobe 21 places cylinder 20 3 in communication with the engine cylinder during its combustion stroke and permits the high pressure gases to enter the compressor cylinder and augment the charge which has been 25 previously drawn into the compressor from the crank case. On the up stroke of the compressor piston 3, the combined charge of mixture from the crank case, and high pressure gases from the engine cylinder will be introduced into the next cylinder firing in the regular rotation and 30 the charge will be under a considerably higher pressure than it would have been if the charge

consisted only of the mixture drawn into the compressor from the crank case.

While I have illustrated and described a preferred embodiment of my invention, it is understood that this showing and description are illustrative only and that I do not regard the invention as limited to the forms shown and described, except by the terms of the following claims. 5

I claim:

1. A fuel injection unit for a multi-cylinder engine, comprising a single compressor cylinder, a piston in said cylinder, a plurality of successively operated valves controlling the communication between said cylinder and individual 15 engine cylinders, and means for operating each of said valves at two different positions of said piston in one pumping cycle thereof, one for the ejection of fuel and the other to take in engine gases. 20

2. A fuel injection unit for a multi-cylinder engine, comprising a single compressor cylinder, a piston in said cylinder, a plurality of successively operated valves controlling the communication between said cylinder and individual en- 25 gine cylinders, and a plurality of angularly spaced cams for opening each valve at two different piston positions, one for the ejection of fuel and the other to take in engine gases. 30

WALDO G. GERNANDT.
